UNITED STATES PATENT OFFICE.

DATUS C. SMITH, OF NEW YORK, N. Y.

DESIGN FOR A BARBED FENCE-WIRE.

SPECIFICATION forming part of Design No. 35,212, dated October 22, 1901.

Application filed July 18, 1901. Serial No. 68,850. Term of patent 14 years.

To all whom it may concern:

Be it known that I, DATUS C. SMITH, a citizen of the United States, residing at New York, in the county of New York and State of New York, have invented and produced a new and original Design for Barbed Fence-Wires; and I do hereby declare the following to be a full, clear, and exact description of the invention, such as will enable others skilled in the art to which it appertains to make and use the same.

In the accompanying drawings, which are to be taken as a part of this specification, Figure 1 represents a plan view of a broken-away portion or section of a barbed fence-wire, showing my new design; and Fig. 2 is a side view of the same.

As shown in the drawings, the said barbed fence-wire consists of a single strand or wire A, having at suitable intervals therein crimps or bends, one of which is denoted by the letter B, and also at intervals other crimps, one of which is shown at C, the latter being provided with fixed sharp-pointed barbs D, said barbs presenting the appearance of prongs whose bases are coiled around different portions of the crimp or bend with a connecting portion bent or coiled tightly about the inter-

mediate portion of the bend or bulge at an angle to said coils and prongs.

As will be seen, the leading or material features of my design reside in a single strand or wire having crimps or bends therein at intervals and also having at intervals other crimps or bends provided with sharp-pointed barbs, the intermediate portions of which appear coiled about the wire at said crimps in such manner that the members of the barb that encircle the wire present themselves at different angles to one another and also wind about different angles formed in the wire by the crimp, thus rigidly fixing the barb to the wire and leaving prongs projecting outwardly at an angle to the body of the wire.

Having thus described my invention, what I claim as new, and desire to secure by Letters Patent, is—

The design for a barbed fence-wire, substantially as herein shown and described.

In testimony whereof I affix my signature in presence of two witnesses.

DATUS C. SMITH.
